UNITED STATES PATENT OFFICE.

EDWARD FRANK KUNATH, OF JERSEY CITY, NEW JERSEY, ASSIGNOR TO UNDERWOOD TYPEWRITER COMPANY, OF NEW YORK, N. Y., A CORPORATION OF NEW JERSEY.

TYPE-WRITING MACHINE.

No. 928,987.

Specification of Letters Patent.

Patented July 27, 1909.

Application filed April 27, 1907. Serial No. 370,627.

To all whom it may concern:

Be it known that I, EDWARD F. KUNATH, a citizen of the United States, residing in Jersey City, in the county of Hudson and State of New Jersey, have invented certain new and useful Improvements in Type-Writing Machines, of which the following is a specification.

This invention relates to the ribbon mechanism of typewriting machines, and particularly to means for bringing into use either of a plurality of ribbons at will.

In certain of my copending applications, two ribbons of different colors are movable independently of one another to cover the printing point at each type stroke. The ribbons are superposed or placed one in front of the other in front of the platen, and one of the ribbons covers and uncovers the printing point during the type strokes, while the other ribbon remains idle.

The object of the present invention is to provide simple, inexpensive and easily operated means which can readily be applied to existing machines for either bringing either ribbon into use and silencing the other one or silencing both simultaneously, at will.

I employ two vibrators or carriers, through which ribbons are threaded, one ribbon in each carrier. Both vibrators I mount upon the usual ribbon vibrating lever of the "Underwood" front strike writing machine, so that both carriers rise and drop together at the type strokes. I further provide means for shifting the carriers relatively to each other, so that one ribbon may stand higher than the other, and hence be brought into use while the other does not reach the printing point. For this purpose, I provide a cross-connection between the upright ribbon carriers at their lower ends, and this cross-connection is directly engaged to the usual ribbon vibrating lever. Said cross-connection is loosely engaged to said lever, so that it may vibrate, one end going up while the other goes down, whereby one carrier is elevated and the other depressed.

In the accompanying drawings, Figure 1 is a perspective rear view illustrating my improvements applied to an "Underwood" front strike writing machine. Fig. 2 is a sectional side elevation showing a type bar in printing position, and the type striking through one ribbon against the front of the

platen. Fig. 3 is a plan of the two ribbon carriers. Fig. 4 is a view like Fig. 2, but showing the types printing through the ribbon. Fig. 5 is a rear elevation of the ribbon carriers showing the rear carrier silenced as at Fig. 4. Fig. 6 is a view similar to Fig. 5, showing the front carrier silenced as at Fig. 2. Fig. 7 is a view similar to Figs. 5 and 6, but showing both carriers silenced or inoperative as at Fig. 8. Fig. 8 is a view showing the platen and the platen type-bar ribbons as at Fig. 2, but showing both ribbons elevated insufficiently to cover the printing point so that the types strike off from the ribbon, as at Fig. 7.

Upon the front side of a revoluble platen 1 strike types 2 mounted upon type bars 3. In front of the platen is the usual ribbon 6, winding back and forth upon spools 7, 8, the latter mounted on vertical shafts 9, 10. Said ribbon 6 is threaded through an upstanding carrier 23 loosely connected to the front end of a lever 25, which is pivoted upon a shoulder screw 26, the latter threaded into a bracket 27 fixed upon the rear side of a horizontal shift rail 28. Said lever 25 has an arm 29 extending up from said pivot 26 and provided with a laterally projecting pin 30, whereby the lever is operated during the backward and forward movement of a universal bar frame or table 21.

In rear of the main ribbon 6, I stretch a supplemental ribbon 31 of red or other special color, which extends between spools 32, 33, pivoted at the extreme sides of the machine, so that the spools 7, 8, lie between said spools 32, 33. Spools 34, 35 are mounted in front of the spools 7, 8, and the endless ribbon 31 is carried therearound, as seen at Fig. 1, so that said ribbon 31 completely encloses or surrounds the spools 7, 8 with their attached ribbon 6. The ribbon 31 may be wound in the manner set forth in U. S. Patent No. 857,288.

The ribbon 31 is threaded through a ribbon carrier 40 mounted directly behind the carrier 23, and having ears 41 to embrace a fixed vertical guide 42, which in said machine is the type-guiding post. The ribbon carriers are guided between said type-post 42 and a fixed abutment 43; a spring 44 being provided upon the carrier 40 for pressing both carriers lightly forward against said post 42.

It is usual in said "Underwood" machine to shift the platen up to enable the upper case characters to print. For this purpose a shifting frame is provided, of which the shift rail 28 forms a part. The platen 1 is journaled upon a platen frame, (not shown) which has a roll 68 to run upon said shift rail 28. The latter is shifted up at the case-shifting operation, and with it rise the bracket 27, the lever 25 and the ribbon carriers 23 and 40, together with the ribbon carried thereby; the deep vertical slot 52 in the ribbon actuator accommodating the up and down movements of the lever pin 30. Thus the operation of causing either ribbon to cover the printing point at the type strokes is carried on the same whether the platen is shifted up or down.

At its lower end the carrier 40 is formed with an ear or offset 69 at one side of the lever 25, and the carrier 23 has an offset 70 at the opposite side of the lever 25; a yoke or lever 71 being pivoted at its ends to said offsets, as at 72, 73. Midway of its ends, said yoke 71 is formed with a ball portion 74, which is detachably inserted in an eye 75 usually provided upon the front of the lever 25, said ball forming a universal joint between the lever and the yoke to accommodate the vibratory movements of both. The forward carrier is provided with a finger piece 76, and when the latter is depressed, the carrier is forced down together with the ear 70 thereon, thus vibrating the yoke 71, and raising the ear 69 together with the carrier 40 to the position seen at Figs. 2 and 6. When the finger piece 76 is lifted, the yoke 71 is vibrated in the opposite direction, so that the carrier 40 is silenced, and the carrier 23 brought up to work, as at Figs. 4 and 5. The eye 75 in the lever serves as a fulcrum for the yoke 71 during the operation of shifting the carriers.

The carrier 40 may be provided with a vertical slot 77, and the carrier 23 may have a guide-pin 78 working in said slot, thereby keeping the carrier 23 in vertical position. The pin 78 further serves as a stop, since by engagement with the ends of said slot, it 50 serves to limit the relative movements of the ribbon carriers.

At Figs. 5, 6 and 7, the lever 25 is shown as vibrated up to the extreme limit of its movement at the type stroke; the types 2 printing through the ribbon 6, at Fig. 5, and 55 through the ribbon 31, at Fig. 6, but printing above or striking off from both ribbons at Fig. 7 for writing stencils. In other words, the movement of the link 71 from either Fig. 6 or Fig. 6 position to Fig. 7 position is insufficient to set both vibrators to ineffective positions; said vibrators at this time preferably coinciding as shown. In practice, there 60 is sufficient friction between the vibrators to enable them to retain the Fig. 7 position,

while the types are operative; and the vibration of the lever 25 does not tend to disturb this arrangement.

Variations may be resorted to within the scope of the invention, and portions of the 70 improvements may be used without others.

Having thus described my invention, I claim:

1. In a typewriting machine, the combination with means for carrying a pair of ribbons one behind the other, of two ribbon vibrators one behind the other, a link connecting said vibrators, and a member reciprocating at the type strokes and connected to said link in such a manner that when either vibrator is manually shifted up or down, the other vibrator is given an opposite movement by said link; said vibrators being normally below the printing point, and being manually adjustable together with said link 80 to a position relatively to said reciprocating member such that neither vibrator causes its ribbon to cover the printing point at the type strokes.

2. In a typewriting machine, the combination with spools for carrying a pair of ribbons, of a pair of ribbon vibrators one behind the other, means for reciprocating said vibrators at the type strokes, and means to enable each vibrator to shift the other vibrator to an effective position, the vibrators being also simultaneously shiftable to idle position, to prevent the ribbon carried by either vibrator from covering the printing point at the type strokes.

3. In a typewriting machine, the combination with a lever which vibrates at the type strokes, of a short link pivoted between its ends on said vibrating lever and moving the two ribbons together toward and away from the printing point, and adjustable to bring both vibrators into a position of disuse at the same time, and also to bring either vibrator to a position of use and the other to a position of disuse, when said lever is in 100 printing position.

4. In a typewriting machine, the combination with means for supporting a pair of ribbons, of two ribbon vibrators, one for each ribbon, means for reciprocating said vibrators at the type strokes, and means for effecting relative adjustment of said vibrators relatively to the printing point to shift both vibrators to ineffective positions at the same time, or to shift either vibrator 115 to a position of disuse and cause the other to be brought into effective position when the type is at the printing point.

5. In a typewriting machine having means for supporting a pair of ribbons, the combination of two ribbon-vibrators, one for each ribbon, means for reciprocating the vibrators in unison at the type strokes, adjustable means connecting said vibrators to move them simultaneously to ineffective positions 125 130

or to move either to effective position and cause the other to be brought to a different ineffective position when the type is at the printing point.

5 6. In a typewriting machine having means for supporting a pair of ribbons, the combination of a device reciprocating at the type strokes, a pair of vibrators reciprocated in unison by said device, and means for effecting relative adjustment of said vibrators to shift both at the same time to ineffective positions or to shift either one to a position of disuse and cause the other to be brought into effective position when the type is at the printing point.

10 7. In a typewriting machine having means for carrying a pair of ribbons, the combination of two vibrators, a link connecting said vibrators, and a member reciprocating at the type strokes and connected to said link to reciprocate said vibrators; said vibrators being relatively adjustable upon said link either to silence or shift both vibrators to a position of disuse simultaneously, or to shift 15 either one of them to a position of disuse and cause the other one to be brought into effective position when the type is at the printing point.

20 8. In a typewriting machine, the combination with means for supporting a pair of ribbons, of a pair of superposed vibrators, means for reciprocating them in unison at the type strokes, and means for effecting relative adjustment of said vibrators in opposite directions either to shift both of them simultaneously to a position of disuse, or to shift either thereof to a position of disuse and cause the other to be brought into effective position when the type is at the 25 printing point.

30 9. In a typewriting machine, the combination of a lever vibrating at the type strokes, a pair of ribbon carriers, and a link engaged by said lever midway between the 35 ends of the link and connecting said carriers, the link being oscillatable upon said lever to shift both carriers to positions of disuse simultaneously, or to shift either vibrator to effective position and cause the other vibrator to be brought to a different 40 position of disuse when the type is at the printing point.

45 10. In a typewriting machine, the combination with means for carrying a pair of ribbons one behind the other, of two ribbon vibrators one behind the other, a link connecting said vibrators, and a member reciprocating at the type strokes and connected to said link, in such a manner, that 50 when either vibrator is manually shifted up or down, the other vibrator is given an opposite movement by said link.

55 11. In a typewriting machine, the combination with spools for carrying a pair of ribbons, of a pair of ribbon vibrators one

behind the other, means for reciprocating said vibrators at the type strokes, and means for enabling either vibrator to be shifted into position of disuse, and to shift the other vibrator to such relation to the reciprocating means as to be effectively operated by the latter.

60 12. In a typewriting machine, the combination with a ribbon vibrating lever, of a pair of ribbon vibrators, one behind the other, and a link connecting said vibrators; said lever being connected by a universal joint to said link midway between the ends of the latter.

65 13. In a typewriting machine, the combination with a ribbon vibrating lever, of a pair of ribbon carriers, one behind the other, and a link connecting said vibrators; said lever being connected by a universal joint to said link midway between the ends of the latter; said ribbon carriers having offset lower ends, which are attached to said link.

70 14. In a typewriting machine, the combination with means for supporting a pair of ribbons, of two ribbon vibrators, one for each ribbon, means for reciprocating said vibrators at the type strokes, and means for effecting adjustment of said vibrators relatively to the reciprocating means and to each other to enable either to be effectively operated by the reciprocating means.

75 15. In a typewriting machine having means for supporting a pair of ribbons, the combination of two ribbon vibrators, one for each ribbon, and means for reciprocating said vibrators in unison, and adjustable means connecting said vibrators to move either to a position to be effectively operated by the reciprocating means and the other to a position of disuse.

80 16. In a typewriting machine having means for supporting a pair of ribbons, the combination of a device reciprocating at the type strokes, a pair of vibrators reciprocated in unison by said device, and means for effecting relative adjustment of said vibrators to shift either one to a position of disuse and cause the other to be brought into effective position when the type is at the 85 printing point.

90 17. In a typewriting machine having means for carrying a pair of ribbons, the combination of two vibrators, a link connecting said vibrators, and a member reciprocating at the type strokes and connected to said link to reciprocate said vibrators; said vibrators being relatively adjustable upon said link to shift either one of them to a position of disuse and cause the other to be brought into effective position when the type is at the 95 printing point.

100 18. In a typewriting machine, the combination with means for supporting a pair of ribbons, of a pair of superposed vibrators,

- means for reciprocating them in unison at the type strokes, and means for effecting relative adjustment of said vibrators to shift either thereof to a position of disuse 5 and cause the other to be brought into effective position when the type is at the printing point.
19. In combination, a lever, a pair of ribbon vibrators, and a link connecting said vibrators and engaged by said lever; the link being oscillatable upon said lever to shift either vibrator to effective position and cause the other vibrator to be brought to a position of disuse when the type is at the 15 printing point.
20. In a typewriting machine, the combination of a lever vibrating at the type strokes, a pair of ribbon carriers, and a link connecting said carriers and engaged by said 20 lever midway between its ends; the link being oscillatable upon said lever to shift either vibrator to effective position and cause the other vibrator to be brought to a position of disuse when the type is at the 25 printing point.
21. The combination of a plurality of ribbons, means for vibrating said ribbons together toward and from the printing point, and means for shifting said ribbons into different relative positions to place any one of 30 said ribbons in a position to be vibrated by said vibrating means to and from the printing position, substantially as set forth.
22. The combination of a plurality of ribbons, means for vibrating said ribbons together widthwise toward and from the printing point, and means for shifting said ribbons into different positions to place one in 35 position to be reciprocated by said vibrating means to and from the printing position and to place another out of such position, substantially as set forth.
23. The combination of a plurality of ribbons, means for vibrating said ribbons together toward and from the printing point, and means for shifting said ribbons in opposite directions to place one in and another out of position for use, substantially as set forth.
- 50 24. The combination of a plurality of ribbons, separate guides therefor, means for vibrating said guides together, and means for changing the relative position of said guides, substantially as set forth.
- 55 25. The combination of a vibrating support, a plurality of ribbons connected thereto and vibrated thereby, and means for changing the relation of said ribbons to each other and to said vibrating support whereby any 60 one of said ribbons can be placed in position for use, substantially as set forth.

26. The combination of a vibrating support, separate guides for a plurality of ribbons supported and vibrated thereby, and means for simultaneously shifting said guides into different relative positions on said support, substantially as set forth. 65
27. The combination of a vibrating support, guides for two ribbons supported and vibrated thereby, and means for shifting said guides in opposite directions on said support to reverse the position of said ribbons, substantially as set forth. 70
28. The combination of a vibrating support, guides supported and vibrated thereby, two ribbons passing through said guides, means for feeding said ribbons lengthwise, and means for moving said guides crosswise of the ribbons to place said ribbons in different relative positions, substantially as set 75 forth.
29. The combination of a plurality of ribbons, means for vibrating said ribbons together toward and from the printing point, and means for shifting said ribbons one toward and another away from the printing point to place one in and another out of position for use, substantially as set forth. 80
30. The combination of a plurality of ribbons arranged face to face in different 90 planes, means for vibrating said ribbons together toward and from the printing point, and means for shifting one of said ribbons edgewise past another to place it in position for vibration to and from the printing position, substantially as set forth. 95
31. The combination of a vibrating support, and guides for two ribbons arranged on the support and vibrating therewith, one of said guides overlapping the other and 100 holding its ribbon out of contact with the other ribbon and its guide, substantially as set forth.
32. The combination of a vibrating ribbon support, and guides for two ribbons arranged on the support and vibrating therewith and holding the ribbons with their adjacent edges overlapping, substantially as set forth. 105
33. In a typewriting machine, the combination of two ribbons, vibrators therefor, a universal bar, connections between said vibrators and said bar, and a rocker pivoted midway of its length and connected to each of said vibrators whereby said vibrators may 110 be moved simultaneously in opposite directions. 115
